CLAIM

We claim the ornamental design for a liner for a bucket, as shown and described.

DESCRIPTION

FIG. 1 is a front perspective view of a liner for a bucket in an assembled configuration;

FIG. 2 is a rear perspective view thereof;

FIG. 3 is a front perspective view thereof with a top portion opened;

FIG. 4 is a left side plan view thereof;

FIG. 5 is a right side plan view thereof;

FIG. 6 is a rear plan view thereof;

FIG. 7 is a front plan view thereof;

FIG. 8 is a top plan view thereof;

FIG. 9 is a bottom plan view thereof;

FIG. 10 is an exploded, perspective view of a partially assembled configuration of the embodiment of FIG. 1;

FIG. 11 is a top plan view of an unassembled configuration of the embodiment of FIG. 1; and,

FIG. 12 is a bottom plan view of the unassembled configuration.
